(57) **CLAIM**

The ornamental design for a cap for writing instruments as shown and described.

DESCRIPTION

FIG. 1 is a front view of a cap for writing instruments showing my new design.

FIG. 2 is a rear view thereof;

FIG. 3 is a right side view thereof;

FIG. 4 is a left side view thereof;

FIG. 5 is top view thereof;

FIG. 6 is a bottom view thereof; and,

FIG. 7 is a an upper perspective view thereof.

The dash-dash broken lines in the drawings represent portions of the article that form no part of the claimed design. The dot-dash broken line represents the bounds of the article and forms no part of the claimed design.

1 Claim, 7 Drawing Sheets
